Carl O. Peterson and Norman J. Spindler, Jamestown, N. Y., assignors to Watson Manufacturing Company, Inc., Jamestown, N. Y., a corporation of New York

Application March 9, 1953, Serial No. 23,949

Term of patent 14 years

(Cl. D33—7)

To all whom it may concern:

Be it known that we, Carl O. Peterson and Norman J. Spindler, citizens of the United States, residing at Jamestown, in the county of Chautauqua and State of New York, have invented a new, original, and ornamental Design for a Desk, of which the following is a specification, reference being had to the accompanying drawing, forming part thereof, and in which:

Fig. 1 is a front elevational view of a desk, showing our new design, the spaced movable covers being in closed position, and the intermediate slidable work shelves placed therebetween;

Fig. 2 is a top plan view thereof, one cover being open, and a slidable work shelf being shown in a different position;

Fig. 3 is an end elevational view thereof, with both covers in closed position.

Fig. 4 is an end elevational view thereof with the cover open.

We claim:

The ornamental design for a desk, substantially as shown and described.
